UNITED STATES PATENT OFFICE.

WELLINGTON RANDALL, OF MARYSVILLE, WASHINGTON.

LIFTING-TONGS.

1,111,322.

Specification of Letters Patent Patented Sept. 22, 1914.

Application filed April 27, 1914. Serial No. 834,825.

To all whom it may concern:

Be it known that I, WELLINGTON RANDALL, a citizen of the United States, residing at Marysville, in the county of Snohomish and State of Washington, have invented certain new and useful Improvements in Lifting-Tongs; and I do hereby declare the following to be a full, clear, and exact description of the invention, such as will enable others skilled in the art to which it appertains to make and use the same.

My invention is directed to improvements in lifting tongs and its primary object is the provision of a device of this character where- 15 in the initial upward or lifting movement thereof will bring about an automatic closing of the jaws upon the object to be hoisted.

A further object of the invention is the provision of a lifting tongs which shall be 20 simple, durable and efficient, which shall be easy and positive of operation, and which may be manufactured and sold at a comparatively low cost.

With the above and other objects in view, 25 the invention consists of the construction, combination and arrangement of parts hereinafter fully described and claimed, and illustrated in the accompanying drawings, wherein,

30 Figure 1 is a view in side elevation of a lifting tongs constructed in accordance with my invention. Fig. 2 is a sectional view taken on the vertical plane indicated by the line 2—2 of Fig. 1, looking in the direction indicated by the arrow. Fig. 3 is a view in side elevation of a modified form of the lifting tongs. Fig. 4 is a sectional view taken on a plane extending centrally and vertically 35 through the modified form. Fig. 5 is a sectional view taken on the vertical plane indicated by the line 5—5 of Fig. 3, looking in the direction indicated by the arrow. Fig. 6 is a sectional view taken on the horizontal plane indicated by the line 6—6 of Fig. 3, looking in the direction indicated by the arrow.

Referring to the drawings by reference numerals, 1 designates the body of my improved hoisting tongs, the same being of 40 hollow cylindrical formation. At its lower end the body 1 is bent inwardly and formed to provide a depending pair of pivot lugs 2. A pair of jaws 3 is pivoted to and between the lugs 2 by means of a bolt 4. Each jaw 45 3 is curved and terminates at its lower end

in a gripping point 6 and provided at its upper end with a straight arm 7. The arms 7 cross each other and their upper free ends are located above the pivot 4 and disposed on opposite sides of the body 1. A member or sleeve 8 is slidably mounted upon the body 1 and is provided at diametrically opposite points with pairs of pivot lugs 9. A pair of links or connecting rods 10 is pivotally secured at their lower ends to the upper ends of the arms 7, as at 11. The upper ends of the links 10 are secured to and between the lugs 9 by pivots 12. As the sleeve 8 is slidably mounted upon the body 1 and owing to its connection with the arms 7, the downward movement thereof will open the jaws, while an upward movement thereof will close the jaws. The upper end of the body 1 has threadedly secured thereto a cap 13 provided with an eye 14.

To permit the jaws 3 to be opened from the hoisting engine during or at the end of the downward movement of the tongs, cables 15 are provided. The cables 15 pass downwardly through openings 16 in the cap 13, 80 then under pulleys 17, and then are attached to hooks 18. The pulleys 17 are journaled, as at 19, at a point below the sleeve 8 and the hooks 18 are carried by and depend from the sleeve 8. It should be apparent that by 85 holding the cables 15 against movement during the downward movement of the tongs, the sleeve 8 will be pulled downwardly upon the body 1, resulting in the jaws 3 being moved into and held in opened position.

To permit the closing of the jaws 3 from the hoisting engine, I provide cables 20 which pass under pulleys 21 journaled on the sleeve 8. By a proper handling of the cables 20, the sleeve 8 may be caused to move 95 upwardly upon the body 1, moving the jaws 3 into closed position about the article to be hoisted. These cables may be used to hoist the tongs and move the article to any point desired.

In its modification, the tongs comprises an elongated body 1^a of rectangular cross sectional configuration. The body 1^a is provided with a slot 22 extending longitudinally thereof and opening at its sides through the sides of the body 1^a. At its lower end the body 1^a is bifurcated to provide a pair of depending pivot lugs 23 to and between which is pivoted a jaw 24 and a pair of jaws 24^a. The jaws 24 and 24^a 110

are pivoted to the lugs 23 through the medium of a bolt 25. The jaws 24^a are arranged in relatively spaced relation to receive between them the jaw 24. The jaws 5 are curved and terminate in their lower ends in points 26. At their upper ends the jaws 24 and 24^a are provided with upwardly and inwardly curved arms 27. A member or block 28 is slidably mounted in the slot 22 10 and projecting from opposite sides thereof are lugs 29. Links 30 are pivoted at their upper ends to the lugs 29 and at their lower ends to the upper ends of the arms 27. The connection between the block 28 and the 15 arms 27 is such that a downward movement of the former with relation to the pivot 25 will open the jaws 24 and 24^a and such that an upward movement thereof with relation to the pivot will close the jaws. The block 20 28 is provided with flanges 30^a adapted to engage the sides of the body 1^a so as to guide the block in its movements on the body. To permit the jaws 3 to be opened 25 from the hoisting engine during or at the end of the downward movement of the tongs, a cable 31 is provided, said cable passing downwardly through an opening 32 in the upper end of the body 1^a, and under a pulley 33 journaled in the slot at a point adjacent 30 its lower end. The cable 31 is then attached to the under side of the block 28, as at 34. To permit the jaws 24 and 24^a to be closed from the hoisting engine I provide a cable 35 which passes downwardly through an 35 opening 36 in the upper end of the body 1, and under a pulley 37 journaled in the upper side of the block 28. The end of the cable is secured to the upper end of the body 1^a, as at 38. To permit the cable 31 to pass between it and the body 1^a the block 20 is provided with a groove 39, as clearly shown in Fig. 6 of the drawing.

It should be apparent from the above description, taken in connection with the accompanying drawings, that I provide a tongs which is fully and completely under the control of the hoisting engine, that is to say, the tongs may be closed and opened from the hoisting engine. The structure is strong,

durable and efficient, and includes comparatively few parts. 50

Various changes may be made in the details of construction without departing from the spirit and scope of the invention as defined in the claims. 55

Having thus described the invention, what is claimed as new, is:—

1. A pair of tongs comprising a body, jaws pivoted to the body, a member slidably mounted upon the body, links connecting the member and jaws, a jaw closing cable operatively associated with the member, and a jaw opening cable operatively associated with the member. 60

2. A pair of tongs comprising a body, jaws pivoted to the body, a member slidably mounted on the body, links connecting the member and jaws, a pulley journaled on the body below the member, a jaw opening cable passing under the pulley and attached 70 at one end to the member, and a jaw closing cable operatively associated with the member. 65

3. A pair of tongs comprising a hollow body, jaws pivoted to the body, a member 75 slidably mounted upon the body, links connecting the member and jaws, a pulley journaled on the body at a point below the member, a jaw opening cable entering the body and passing under the pulley and attached 80 at one end to the member, a pulley journaled on the member, and a jaw closing cable passing under said last named pulley. 85

4. A pair of tongs comprising a body, a member slidably mounted upon the body, 90 jaws pivoted to the body, links connecting the member and jaws, pulleys journaled on the body below the member, jaw opening cables passing under the pulley and attached to the member, pulleys journaled on the member, and jaw closing cables passing under the last named pulleys. 95

In testimony whereof I affix my signature in presence of two witnesses.

WELLINGTON RANDALL.
